United States Patent Office.

CHARLES L. MOREHOUSE, OF CLEVELAND, OHIO.

Design No. 3,561, dated June 29, 1869.

DESIGN FOR A TRADE-MARK.

The Schedule referred to in these Letters Patent and making part of the same.

To all whom it may concern:

Be it known that I, CHARLES L. MOREHOUSE, of Cleveland, in the county of Cuyahoga, and State of Ohio, have invented certain new and useful Improvements in a Design for a Trade-Mark; and I do hereby declare that the following is a full and complete description of the same.

This invention relates to a design for a trade-mark, the same to be placed upon oil-barrels, to indicate the nature of the contents thereof.

The character of said design is as follows:

It is of a circular form, the outer rim or margin of which is made up of the name of the company, "Morehouse, Freeman, and Crumb," by whom the oil is manufactured, and the words "Cleveland, Ohio," the name of the place and State of the company and manufactory.

Within the upper side of the border of the design, are arranged five star-like figures, A, on which the letters of the word "trade" are displayed.

Within the lower side of the border are arranged four similar-shaped figures, B, on which the letters of the word "mark" are displayed.

Across the diameter of the design, between the words "trade" and "mark," is displayed the word "machinery."

Above the first two and last two letters of the word, is an ornamental scroll, and immediately under the word, is the word "oil," the whole reading thus:

"Morehouse, Freeman, and Crumb, Cleveland, Ohio. Machinery-oil. Trade-mark."

What I claim as my invention, and desire to secure by Letters Patent, is—

A design for a trade-mark, substantially as herein described and for the purpose specified.

CHARLES L. MOREHOUSE.
